UNITED STATES PATENT OFFICE.

HOWARD TERHUNE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

DROP-HAMMER.

1,246,184.

Specification of Letters Patent. Patented Nov. 13, 1917.

Application filed June 26, 1916. Serial No. 105,870.

To all whom it may concern:

Be it known that I, HOWARD TERHUNE, a citizen of the United States, and a resident of Chambersburg, in the county of Franklin and State of Pennsylvania, have invented certain new and useful Improvements in Drop-Hammers, of which the following is a specification.

My invention relates to improvements in drop hammers and more particularly to an improved means for securing the frame of the hammer to the anvil, my present invention being an improvement upon the frame adjusting means shown in United States Patent No. 1,044,292 issued to me upon November 12, 1912. In the above patent the frame was secured to the anvil by adjusting bolts provided with hooked heads, the anvil adjacent said heads being provided with an undercut recess for the reception of the correspondingly formed part of the bolt head, which tightly fits said recess and which also tightly fits a recess or pocket in the frame. Experience has shown that this arrangement is not satisfactory as the jar incident to the operation of the hammer presently crystallizes the bolt which breaks through the head.

The purpose of the present invention is to furnish a means for securing the frame and anvil which will prove durable against the strains to which it is subjected.

A further purpose of my invention is to balance the strains upon the bolt securing a drop hammer frame to its anvil and to reinforce the bolt by a balanced reinforcement.

A further purpose of my invention is to support a reinforced bolt adapted to balance the strains in drop hammer frame and anvil retention by a projection to maintain the bolt in position.

In the accompanying drawings forming part of this specification and in which similar letters of reference indicate similar parts throughout the several views:—

Figure 1, is a side elevation of a board drop hammer frame furnished with my improved means for securing the frame and anvil:

Fig. 2, a plan view, and Fig. 3 a side elevation, of my reinforced bolt for securing the frame and anvil:

Fig. 4, a front elevation, partly in section,

of part of the frame and anvil showing my improved means for securing these parts: 55

Fig. 5, a section of Fig. 4 on line A—A.

1 is the anvil of a drop hammer upon which is mounted the frame 2 the legs of the latter being furnished with tongues 14 which are carried in suitable grooves in the 60 anvil. The tongues 14 are beveled on their inner ends, as shown in Fig. 5, to receive the reinforced heads of the bolts 13 which adjustably secure the sides of the frame 2 to the anvil. 65

The bolts 13 are shown in plan and side elevation in Figs. 2 and 3 from which it will be observed that they have long T heads 4 heavily reinforced at 5 where they join the body of the bolt. The overhanging head of 70 the bolt is supported on the underside by the lip 6 extending down from it and resting upon the top of the anvil as shown best in Fig. 4.

The body of the bolt has a bearing in the 75 frame 2 and its end is threaded and preferably furnished with a keeper similar to that shown in my former patent, that is to say a nut 16 having a notched collar 17 which is engaged by a spring depressed tooth 19 carried by frame 2.

By these means I obtain the effect of a body bound bolt bridging the gap in an anvil and taking the strains to which it is subjected in tension. 85

The bolt can readily be removed or replaced without lifting the frame from the anvil, and there are no projecting ears or lugs on either frame or anvil to break off during the working of the hammer, all strain being taken by the anvil at the front of the frame seat by the guide of the frame in the anvil, and by the heavily reinforced tension bolt. 90

The frame 2 is held against vertical movement on the anvil by the bolts 10 as in my former invention above referred to. 95

Having thus described my invention I claim as new and desire to secure by Letters Patent:—

1. In a drop hammer, the combination of a hammer, an anvil laterally grooved and recessed toward the front and back from the groove, a frame tongued to fit the groove and having an opening extending longitudinally of the tongue, a bolt adapted to lie 100 105

- in said opening and having a T-shaped head adapted to engage the anvil upon opposite sides of the tongue and a nut engaging the tongue of the frame to tend to move the frame with respect to the anvil.
2. In a drop hammer, the combination of a hammer, an anvil therefor, a frame movable relatively to the anvil, a bolt passing through a portion of the frame and having a reinforced T-head adapted to engage the anvil on opposite sides and a nut for the bolt adapted to engage the frame.
3. In a drop hammer, the combination of a hammer, a frame and anvil movable relatively to one another, the frame having a tongue extending into a groove in the anvil, a T-headed bolt having the head of the T thickened transversely, a tapered extension of said transverse thickening extending toward the threaded portion of the bolt from the head, the head adapted to engage the anvil on opposite sides of the tongue and a nut for the other end of the bolt adapted to engage the tongue.
4. In a drop hammer, the combination of a hammer, a frame and anvil movable relatively to one another, a tongue upon the frame adapted to move in a groove in the anvil, a T-headed bolt engaging the anvil on opposite sides of the tongue and having the connection between the head and stem tapered, a transverse extension of the head adapted to support the head on the anvil against vertical movement and a nut on the bolt adapted to engage the tongue.
5. In a drop hammer, the combination of a hammer, an anvil and a frame, said anvil being planed out for the reception of tongues upon said frame, said anvil and frame being movable relatively to one another and means for adjusting said parts consisting of bolts passing through said tongues having heavily reinforced T-heads engaging the anvil and lips under said heads also engaging the anvil and supporting them and nuts upon the outer ends of said bolts bearing against said frame.

HOWARD TERHUNE.
